UNITED STATES PATENT OFFICE

PAUL PETER SULLIVAN, OF CHICAGO, ILLINOIS

WINDOW FRAME AND SASH THEREFOR

Application filed November 6, 1930. Serial No. 493,846.

This invention relates to certain new and useful improvements in windows, and has more particular reference to a window frame and sash therefor.

8 A primary object of this invention is to provide a window construction including a sash and frame especially, but not essentially adapted for use in railway car constructions and more particularly for use on the vestibule 10 of street railway cars.

A still further object of the invention is to provide a structure of the above mentioned character which will be stormproof, and which will further serve the purpose of keeping out dust and the like.

A still further object of the invention is to provide a window frame and sash therefor which will be strong, durable, will present a neat and attractive appearance and which 20 will be well adapted for the purpose designed.

Other objects and advantages of the invention will become apparent during a study of the following description, taken in connection with the accompanying drawings, wherein:

25 Figure 1 is an elevational view of the structure showing the window in a closed position and viewing the structure from the inside of the car.

Figure 2 is a view similar to Figure 1 viewing the structure exteriorly of the car.

Figure 3 is a longitudinal vertical sectional view, certain parts being shown in elevation.

Figure 4 is a vertical transverse sectional view taken substantially on the line 4—4 of 35 Figure 1.

Figure 5 is a similar view taken substantially on line 5—5 of Figure 1.

Figure 6 is a horizontal detail sectional view taken substantially on line 6—6 of 40 Figure 1.

Figure 7 is a perspective view of the window sash.

Figure 8 is a perspective view of a guide and retaining plate forming part of the invention.

With reference more in detail to the drawings, it will be seen that the frame is designed generally by the reference character F. The frame F is preferably formed of 50 metal, and comprises two vertical side sections

designated generally by the reference characters A and B respectively.

Each of the sides A and B comprises a single inner vertically disposed plate 1 provided on opposite longitudinal edges thereof with inwardly directed flanges 2. The plate 1 has integral therewith and extending from the upper to the lower edge thereof a hollow rib 3. The outer vertical face of the rib 3 is disposed beyond the vertical edges of the flanges 2 and said rib 3 on said outer vertical face is provided with a series of vertically spaced bolt receiving apertures 4.

The rib serves to support in spaced parallel relation to the plate 1 a pair of vertically aligned half plates 5 secured one above the other in end to end relation through the medium of bolts 6 passing through the half plates, and the bolt accommodating openings 4. The rib 3 is opened at the upper and lower 70 ends thereof to facilitate the threading of nuts 7 on the inner ends of bolts 6.

From the description thus far, it will be apparent that the side B is substantially one-half of the side A.

Each of the plates 5—5 of the respective sides A and B at their free vertical edges, are provided with inwardly directed flanges 8 which at their inner vertical edges terminate in spaced parallel relation to the vertical 80 edges of the flanges 2 thus providing therebetween vertical guide slots 9.

The sides A and B of the frame, are arranged in vertical spaced relation, to provide therebetween a window opening O. Slidable vertically within the opening, between the opposed edges of the sides A and B is a window sash designated by the reference character S.

The window sash S comprises a substantially rectangular frame like structure including top and bottom members 11 and 12 respectively, and side members 13 and 14 respectively.

Each of the side members 13 and 14 is provided with a laterally directed flange or plate 15. The flanges or plates 15 operate in the guide slots 9 of the respective side members A and B and to each of the plates 15 are suitably bolted as at 16 a pair of plates 17.

Each of the plates 17 adjacent one vertical edge thereof is provided with a laterally offset jaw 18. The jaws 18 of the respective pairs of plates are adapted to receive therebetween a guide rod or post 19 disposed on one side of the rib 3 of the respective side members A and B, and integral with the rib.

Completing the structure of the window, there is arranged within the confines of the window sash S and extending longitudinally of the members 11, 12, 13 and 14 of the frame of the window sash, the members 20 of a retaining frame.

Each of the frame members 20 is provided with a suitable notch 21 for accommodating an edge portion of a transparent pane 22. Cooperating with the members 20, for retaining the pane 22 in position, are the members of a substantially rectangular frame 24. The members of the frame 24 are preferably of hollow construction, and the frame is preferably formed of metal. The members of the frame 23 are secured to the frame members 20 through suitable bolts or other fastening elements 25.

Carried by each vertical member of the frame 24, adjacent the lower end of the window sash, is a suitable spring actuated lock bolt structure designated generally by the reference character 25. The inwardly directed flanges 8 of the respective plates 5 are each provided with a vertical series of spaced openings 26 adapted to be selectively engaged by the bolts of the lock bolt structures 25 for retaining the window in either a fully closed or fully opened position, or in a predetermined partially opened or closed condition as is apparent.

Preferably, in actual practice, the plates 1 of the respective members A and B of the frame, are arranged exteriorly of the car, and the plate 5 of the respective members A and B, are arranged interiorly of the car.

Completing the frame F are upper and lower channel members 28 and 29 respectively. The upper and lower members 28 and 29, connect the vertical side members A and B of the frame and suitably close the space between the plates 1 and the pairs of plates 5 of the respective frame members A and B. The said members 28 and 29, being of channel shape in cross section, snugly receives between the sides thereof the horizontal edges of the plate 1, and plates 5, thus preventing the entrance of dirt, rain, sleet or the like into the space between the plates 1, and the pairs of plates 5.

As is apparent, the window when in closed position will close only substantially half of the window opening O, that is the space between the side members A and B of the frame. The window opening O at the upper half thereof is normally closed, through the medium of a suitable plate 30 that extends between the sides A and B. Thus, when the

window is closed, the opening O will also be entirely closed.

It is thought that from the foregoing description, taken in connection with the accompanying drawings, that a clear understanding of the operation, structure, utility and advantages of a window frame and sash as comprehended by the present invention will be had by those skilled in the art without a more detailed description.

Even though I have herein shown and described the preferred embodiment of the invention, it is to be understood that the same is susceptible to changes, modifications and improvements coming within the scope of the appended claims.

Having thus described my invention, what I claim as new is:

1. A window construction comprising in combination a frame including a pair of vertical side members respectively comprising a plate, a rib integral with the plate, a pair of upper and lower half plates secured to said rib in spaced parallel relation to said first mentioned plate, said first mentioned plate and said half plates respectively provided adjacent their vertical edges with inwardly directed flanges, whereby to provide between the flange on the first mentioned plates, and the flanges of said half plates, guide channels, and a window sash operable between said side frame members, said sash provided with lateral oppositely extending plates operable within said guide channels.

2. A window construction comprising in combination a frame including a pair of spaced apart vertical side members respectively comprising a pair of spaced parallel plates, a rib extending parallel to said plates in the space between said plates, a window sash operable within said frame between said side members, said sash provided on opposite sides thereof with lateral plates adapted to extend inwardly of the space between the said plates of the respective side frame members, said ribs, and the said plates carried by said window sash provided with cooperable means for guiding said sash during the raising and lowering of the latter.

3. In a window construction of the character described, a frame including a pair of vertical side members respectively comprising a pair of spaced parallel plates, a rib extending vertically between said plates, said rib provided with a lateral vertically extending guide post, a window sash operable in said frame between said side members, oppositely extending flanges projecting laterally from said sash and operable in the space between the plates of the respective side members of said frame, said flanges respectively provided with a pair of opposed jaws adapted to receive therebetween one of said guide posts.

4. A window construction comprising in

- combination a frame including a side member comprising a pair of spaced parallel plates, a rib extending parallel to said plates in the space between said plates, said plates respectively provided adjacent one edge thereof with an inwardly directed flange, said flanges at their inner vertical edges terminating in spaced parallel relation to provide therebetween a guide slot, a window sash operable in said frame and provided with a laterally directed flange operable within said guide slot, said rib, and the said sash flange of said sash provided with cooperating means for guiding the sash during sliding movement of the latter within said frame.
- 5 5. A window construction comprising in combination a frame including a side member comprising a pair of spaced parallel plates, a rib extending parallel to said plates in the space between said plates, said plates respectively provided adjacent one edge thereof with an inwardly directed flange, said flanges at their inner vertical edges terminating in spaced parallel relation to provide 10 therebetween a guide slot, a window sash operable in said frame and provided with a laterally directed flange operable within said guide slot, said rib, and the said flange of said sash provided with cooperating means for guiding the sash during sliding movement of the latter within said frame, the flange of one of said plates of said side member provided with a vertical series of spaced apertures, and a spring pressed lock bolt 15 carried by said sash for selective engagement with said apertures for retaining said sash in a predetermined raised or lowered position.
6. In a window construction of the character described, a window frame, a pair of parallel guide posts arranged in said frame, a window sash operable in said frame between said post, said sash provided with oppositely extending flanges projecting laterally therefrom, a pair of plates secured to each of said flanges, the plates of said pair respectively provided with a clamping jaw and said guide posts adapted to be received between the jaws of the respective pairs of plates.
- 40 7. In window construction, the combination of a guide post, a sash having a side member provided with a flange projecting laterally therefrom, a pair of plates secured to said flange, said plate being provided with opposed cooperating jaws adapted to receive therebetween said guide post.
- 45 8. A metal window frame comprising a vertical side member having a vertical slot, a vertical guide post arranged in said side member, a sliding sash in said frame and having a flange projecting laterally therefrom and passing through said slot, and opposed jaws provided on said flange and having sliding contact with said guide post.
- 50 9. A window frame comprising in combination a vertical side or jamb member comprising an outer plate provided adjacent its vertical edges with inwardly directed flanges, a hollow rib integral with said plate and extending in spaced parallelism to said flanges, 70 a pair of upper and lower half plates secured to said rib in parallelism to the first mentioned plate, each of said half plates provided with flanges confronting and terminating in spaced parallelism with the flanges of the 75 first mentioned plate and vertical guide posts on opposite sides of said rib.
- In testimony whereof I affix my signature.
